UNITED STATES PATENT OFFICE

100,145

DESIGN FOR A BOX OR THE LIKE

Arthur Bates, North Attleboro, Mass., assignor to
Evans Case Company, a corporation of Massachusetts

Application April 29, 1936, Serial No. 62,375

Term of patent 14 years

To all whom it may concern:

Be it known that I, Arthur Bates, a citizen of the United States, residing at North Attleboro, county of Bristol and State of Massachusetts, have invented a new, original, and ornamental Design for Boxes or the like of which the following is a specification, reference being had to the accompanying drawing forming a part thereof.

The drawing is a perspective view of a box showing my design.

The characteristic feature of the invention resides in a roll of paper or the like simulating a diploma, certificate or the like attached to the exterior of a box the particular shape of the box not being an essential feature of my design.

I claim:

The ornamental design for a box or the like as shown and described.

ARTHUR BATES.
